UNITED STATES PATENT OFFICE.

JOHN A. GUINN, OF PERRY, IOWA.

FIRE-EXTINGUISHER.

SPECIFICATION forming part of Letters Patent No. 440,630, dated November 18, 1890.

Application filed April 14, 1890. Serial No. 347,926. (No model.)

To all whom it may concern:

Be it known that I, JOHN A. GUINN, of Perry, in the county of Dallas, in the State of Iowa, have invented a new and Improved Mode of 5 Extinguishing Fires in Railroad-Car Stoves in Cases of Accident; and I do hereby declare that the following is a full, clear, and exact description of the construction and operation of the same.

10 This invention relates to automatic fire extinguishers.

The object of the invention is to produce a device whereby upon the upsetting, derailing, or other serious accident to a railway-car 15 the fire in the stove will be instantly extinguished.

With this object in view the invention resides in a fire-extinguisher for car-heaters, consisting in the combination, with a tank 20 containing alkali, an acid bottle supported within said tank, a weight supported above said bottle by a coiled spring, said spring being adapted to support the weight out of contact with the bottle during the ordinary motions 25 of the car, but on the occurrence of an unusual shock to allow the same to descend and break the bottle, and suitable connections between the tank and the heater.

In the accompanying drawings, forming 30 part of this specification, and in which like figures of reference indicate corresponding parts in all the drawings, Figure 1 represents a vertical section of a tank containing my device, the same being connected to an ordinary 35 car-stove. Fig. 2 is an enlarged view in section of my device, and Fig. 3 is an enlarged view of the weight and the bottle for containing acid.

In the drawings, 1 represents a car-stove, and 2 a tank containing alkali, which is connected 40 to the stove through the pipe 3.

4 is an upright or stand-pipe, on the top of which is supported a glass bottle 6 containing acid.

7 is a cup supported from the upright 5 by 45 a coil-spring 8, stiff enough to take up the ordinary jarring motion of the car.

8½ is a flanged ball-weight, connected by a chain 9 to the glass bottle 6, so that should the train meet with an accident—a severe 50 crash or an overturn—the ball-weight 8½ will be thrown from its cup, and, directed by the chain, break the bottle 6, and mixing the acid with the chemicals surrounding it in the tank causing the gases and fluid to rush in on the 55 fire through pipe 3, thus extinguishing it.

Having thus fully described my invention, what I claim as new, and desire to secure by Letters Patent, is—

In a fire-extinguisher for car-heaters, the 60 combination of a tank containing alkali, an acid-bottle supported within said tank, a flanged weight supported above said bottle by a coiled spring, said spring being adapted to support the weight out of contact with the 65 bottle during the ordinary motions of the car, but on the occurrence of unusual shocks to allow the same to descend and break the bottle, and suitable connections between the tank and the heater, substantially as de- 70 scribed.

JOHN A. GUINN.
